GUN SLING

Alfred B. Wilber, Caldwell, Idaho

Application May 9, 1950, Serial No. 160,962

2 Claims. (Cl. 24—170)

1

The present invention relates to keepers for use upon rifle slings of the type having double straps extending between the swivel of the rifle and more particularly the keeper is of a quick acting and semi-automatic type which can be employed for adjusting double strap slings.

To increase the accuracy of a rifleman's fire, it is the practice to employ a double strap adjustable sling which extends between the swivel at the butt end of the rifle and the swivel carried by the fore stock of the rifle. The rifleman can extend his left arm through the double straps and by sliding the keeper therealong can tighten the straps around his arm for steadyng his support of the rifle. The present keeper has been conceived for this purpose.

The principal object of the present invention is to provide a keeper for double band slings which can be quickly and easily operated for locking the double band at a point thereof when desired.

A further and important object of the invention is to provide a keeper which is semi-automatic in its operation both when locking and when unlocking and which is simply and economically constructed.

A further object of the invention is to provide a keeper which consists of one unitary member having elements thereof permanently connected to one another.

Referring now more particularly to the accompanying drawings, wherein Fig. 1 is a bottom elevation of a double strap rifle sling with a keeper according to the present invention in its locked position thereon.

Fig. 2 is a side view of Fig. 1.

Fig. 3 is a top view of the present keeper in its locked position upon a sling.

Fig. 4 is a cross-sectional view of Fig. 3 taken on line extending between the double straps of a sling extending therethrough.

Fig. 5 is a view similar to Fig. 4 but with the locking arm pivoted to its unlocking position.

Fig. 6 is a top cross-sectional view taken on line 6—6 of Fig. 4.

Fig. 7 is a further cross-sectional view taken on line 7—7 of Fig. 4.

Fig. 8 is a further cross-sectional view of Fig. 4 taken on line 8—8 thereof.

Fig. 9 is a cross-sectional view taken on line 9—9 of Fig. 5.

Fig. 10 is a vertical cross-sectional view taken on line 10—10 of Fig. 4; and

Fig. 11 is a further cross-sectional view taken on line 11—11 of Fig. 4.

Referring now more particularly to the accom-

panying drawings wherein like and corresponding parts are designated by similar reference characters, Figs. 1 and 2 show a double strap sling which is disclosed as an example only of the type of sling to which the present keeper can be applied. This sling consists of an endless strap having two legs 1 and 2 which are positioned one upon the other with the end 3 of strap 1 positioned within the end 4 of strap 2. Said end 3 has a series of double openings 6 through which extend prongs 5 connected to end 4 whereby the two ends can be adjustably connected for varying the length of the strap. The opposite end of straps 1 and 2 are connected to a second section 15 of the sling as at 7 and said second section also consists of a pair of straps 8 and 9 positioned one upon the other and adjustably connected by prongs 10 extending through one of a series of openings 14 in strap 8. The end 11 of these straps is for attachment to a rifle swivel while the opposite end 12 is formed around a ring 15 and the two straps sewed together. Straps 1 and 2 likewise extend through said ring 15.

The keeper 20 comprising the present invention consists of a pair of flat parallel plates 21 and 22 between which are positioned spacer bars 23 and 25 with bar 23 positioned at the top edge of plates 21, 22 and bar 25 at the bottom edge thereof. These elements are fastened together by a series of rivets 24 extending therethrough at each corner. Said bars 23 and 25 each have a centrally located slot 27 and 26, respectively, formed in one edge thereof and which slots are diametrically opposite to one another.

A locking arm 30 has one end thereof positioned within the slot 27 of bar 23 with rivet 24 passing therethrough for pivotally supporting the same. The intermediate portion 31 of arm 30 has a wedge-shaped cross-sectional configuration as indicated in Figs. 8 and 9 of the drawing with the thin edge thereof directed towards the slide formed by plates 21, 22 and bars 23, 25. The free end of arm 30 forms a handle 32 which can be inserted within and extend from slot 26 of bar 25.

The present keeper is mounted upon a sling by passing the double straps such as 1 and 2 through the centrally located rectangular opening formed within said slide and which opening is particularly sized and shaped for just slidably receiving said straps and guiding the same therethrough.

The keeper 20 can then be slid in either direction as indicated by the arrows in Fig. 1 and when it is desired to lock straps 1 and 2 together, arm 30 is pivoted towards said slide and between said straps whereupon the wedge portion 31 will

force the straps against plates 21 and 22 for frictionally engaging the same. The handle 32 at the same time enters its slot 26 and both slots 26 and 27 guide the arm 30 to prevent a lateral movement thereof.

When it is desired to unlock the keeper, arm 30 is pivoted away from said slide as the same is pivotal in either direction as indicated by the arrows of Fig. 5.

When unlocked the slide can be moved along said sling and when the arm 30 rubs between straps 1 and 2, it will be drawn therewith towards said slide into its locked position. Thus the keeper can be locked by a quick movement thereof to the right of Fig. 1. A quick movement to the left will similarly unlock the same as the straps will draw the locking arm from the slide. Thus the keeper can be locked or unlocked quickly and automatically when desired.

It is to be appreciated that the present keeper can be employed upon all types of double strap slings and the present sling is shown by way of example only. The keeper further can be made of various configurations and sizes without imparting from the spirit of the invention and such changes thereto as come within the scope of the appended claims, are deemed to be a part of the invention.

I claim:

1. A keeper for double strap rifle slings comprising a slide formed with a central opening shaped for slidably receiving and guiding said double straps therethrough and extending from one end to the opposite end of said slide, said slide further having a slot formed in one of said ends thereof and extending across the medial portion of said end, and an arm pivotally mounted

at one end in an end portion of said slot and formed with the opposite end portion thereof capable of being slidably inserted in the opposite end of said slot, and said arm further having a wedge shaped medial portion for insertion in an end of said central opening and between said straps.

2. A keeper for double strap rifle slings comprising a pair of parallel flat plates, a pair of spaced bars positioned between and connected to said plates forming a substantially rectangular opening therebetween for slidably receiving said double straps therethrough, said bars having diametrically opposite slots formed in the medial portion of corresponding ends thereof, and an arm pivotally mounted at one end in one of said bar slots and having its opposite end portion formed for being slidably inserted in the opposite of said bar slots, and said arm further being formed with the medial portion thereof having a wedge shape with the edge thereof extending towards and in line with the medial portion of said rectangular opening.

ALFRED B. WILBER.
